Primary Examiner — Cynthia M Chin(74) *Attorney, Agent, or Firm* — Leber Patent Law P.C.**(57) CLAIM**

What is claimed is the ornamental design for a container closure system with handle, as shown and described.

DESCRIPTION

FIG. 1 is a top-side perspective view of a container closure and pressurization system and handle, showing the new design (the vessel, shown in phantom, does not form part of the present design);

FIG. 2 is a left-side elevational view thereof (the vessel is removed for clarity);

FIG. 3 is a rear elevational view thereof;

FIG. 4 is a right-side elevational view thereof;

FIG. 5 is a bottom view thereof, in which the elements shown in broken lines do not form part of the present design;

FIG. 6 is a front elevational view thereof; and,

FIG. 7 is a top view thereof.
